UNITED STATES PATENT OFFICE.

GYULO ARMENY, OF NEW YORK, N. Y.

DIAMOND-CROSS-CUTTING MACHINE.

SPECIFICATION forming part of Letters Patent No. 697,230, dated April 8, 1902.

Application filed May 22, 1901. Serial No. 61,404. (No model.)

To all whom it may concern:

Be it known that I, GYULO ARMENY, a citizen of the United States, residing in New York, borough of Bronx, in the State of New York, have invented certain new and useful 5 Improvements in Diamond-Cross-Cutting Machines, of which the following is a specification.

This invention relates to diamond-cross-cutting machines; and the object of the invention is to provide a practical, convenient, and efficient machine for cutting across a diamond in a plane transverse to the natural-cleavage direction and by which any part of 15 the diamond, whether at the corner or facet, may be attacked by the cutter for starting the cut.

The invention consists in the combination, in a diamond-cross-cutting machine, means 20 for operating the same, a suitably-supported guide-rail arranged transversely to the cutting-disk, a traverse-slide guided on said guide-rail, a feed-slide guided on the traverse-slide in a line transverse to the line of travel 25 of the traverse-slide, a clutch-holding device mounted on the feed-slide, a pulley at the inner end of the traverse-slide, a weight, a cord connected with said weight and guided over said pulley, and means for connecting said 30 cord at different points in its length with said feed-slide.

In the accompanying drawings, Figure 1 is a side elevation of a diamond-cross-cutting machine, showing my invention. Fig. 2 is a 35 transverse section of the same. Fig. 3 is a plan view. Fig. 4 is a section on line 4-4, Fig. 2, looking in the direction of the arrow. Fig. 5 is a detail section showing the ball-bearing for the cutter-disk. Fig. 6 is a detail view of 40 the clutch, showing how a diamond is supported therein; and Fig. 7 is a detail sectional view showing a modified form of the cutting-disk.

Referring to the drawings, A indicates the 45 base-plate of the machine, provided with brackets *a* at each end, which carry at their upper ends boxes *a'*, in which is rigidly fixed the shaft *B* for the cutting-disk *C*. In the main form of the invention the cutting-disk 50 preferably consists of a very thin disk-shaped sheet of copper or phosphor-bronze, which is retained on the hub *C'* by means of clamping-

plates *C²* *C³* and by a screw-nut *C⁴*, which is screwed onto the screw-threaded end *C⁵* of the hub *C'*. Between the hub *C'* and the shaft *B* 55 antifriction-balls *b* are arranged so as to provide a ball-bearing to reduce the friction, thereby permitting the disk to turn rapidly with a minimum of friction. The hub *C'* serves as a pulley over which a suitable driv- 60 ing belt or band may pass. In Fig. 7 a modification of the cutting-disk is shown applied to the hub, the same consisting of a disk-shaped body of porous soft iron provided with a cutting edge *n* and a thickened portion *n'* 65 and having an internal screw-thread *n²* for screwing directly onto the hub *C'*. Extending around the lower, rear, and upper parts of the cutting-disk *C* is a curved guard-plate 70 *D*, which is secured at its lower end to a fixed pin *d* and which at its upper end is split to provide an ear *d'*, which is secured to one of the boxes *a'* at *d²*.

Arranged upon the upper surface of the base-plate *A* is a foot-plate *E*, which is provided with a longitudinal slot *e*, that extends transversely to the stationary shaft *b* and through which passes a clamping-screw *f*, which fixes the foot-plate adjustably to the base-plate *A*. Under the head of the clamping-screw *f* a washer *f'* is placed. At the forward end of the foot-plate *E* a socket-piece *e'* is formed, into one side of which is screwed a set-screw *e²*, which is adapted to bind upon the lower end of a short pedestal or post *g*, 85 which is inserted into the socket *e'*. The upper end of the pedestal *g* carries a fixed guide piece or rail *G*, which is arranged transversely to the plane of the cutting-disk *C*, and located in front of the same. 90

A traverse-slide *H* has preferably a dovetailed or equivalent connection with the guide-rail *G*, so as to be guided thereon and to be adjustable across the plane of the cutting-disk. The traverse-slide is adjusted by 95 means of a screw-spindle *h*, the ends of which turn in smooth bearings in the ends of the guide-rail *G* and which is provided beyond one end of the latter with a hand-wheel *h'* or other suitable means of rotation, while the screw-threaded portion of the screw-spindle passes through a nut formed by an internally-screw-threaded lug *h²* on the under side of the traverse-slide *H*. The traverse-slide *H*

has a guide rib or portion h^3 , which extends in a plane parallel with the cutting-disk C and which receives a correspondingly-formed, preferably dovetailed, portion of a feed-slide I, which is adapted to support the stone-holding clutch J for feeding it to the cutting-disk.

The feed-slide I is moved toward the cutting-disk by means of a weight K, which is suspended by means of a cord or piece of cat-
10 gut k , that is guided over an idler-pulley k' , mounted in the inner end of the traverse-slide H and extending through a groove or channel h^4 , formed longitudinally in the guide-rail h^3 of the traverse-slide, and which
15 cord is fixed to the feed-slide by means of a removable pin or peg i , that is forced into a perforated downwardly-projecting lug i' at the forward end of the feed-slide and through which perforated lug the outer end of the
20 cord k is passed.

The inner forward end of the feed-slide I is provided with means for holding the clutch J, and this means consists of a post L, which is provided at its lower end with an annular
25 retaining-flange l , which engages a rabbet-groove l' in the lower end of an aperture l^2 in the feed-slide I and upwardly through which aperture the said post L passes. The post L is provided with a transverse opening l^3 , in
30 which the head of the clutch J is set and retained by means of a binding-screw L' , that passes through the upper end of the post and at its lower end bears upon the head of the clutch, so as to bind the same down upon the
35 feed-slide I at opposite sides of the feed-slide aperture l^2 . In this way the binding-screw L' serves the double purpose of retaining the clutch and also setting the post L in fixed position, so that the described clutch-holding
40 device forms a very efficient and positive means for securing the clutch against movement. The means for guiding the traverse-slide and the feed-slide are preferably formed of hardened steel, and the guiding portions
45 must be cut smooth and accurate, so that there will be no loose motion or wabbling of the parts, and these parts may be suitably formed and constructed so as to guide and retain the two slides in their set positions.

50 In operating the described diamond-cross-cutting machine the diamond, such as S, is clamped in the clutch and retained so that it may be cut through and severed in a plane transverse to the planes of cleavage.

55 The clutch J is preferably constructed as shown and claimed in my copending application, Serial No. 47,310, filed February 14, 1901, the space between the jaws being filled with some suitable soft filling x , preferably lead,
60 to prevent accumulation therein of the carbon powder or abradant used with my machine for assuring the cutting action of the cutter. The diamond S is so fixed in the clutch as to project sidewise therefrom. The foot-
65 piece E, the guide-rail G, and the traverse-slide H are now set to the desired position, according to the point at which the cutting-

disk is to attack the diamond, whether it be at the girdle or at either side of the same. The feed-weight K is now fixed in position 70 and set so that it will exert pressure on the feed-slide sufficient to gently force the diamond S against the edge of the cutting-disk C. The cutting-disk is now rapidly rotated by a suitable power-transmitting device, and the 75 carbon particles or powder which are to assist the cutting action and render the same possible are fed in a suitable manner to the edge of the cutting-disk, whereupon the cutting action takes place in a plane transverse 80 to the planes of cleavage of the diamond, and after a sufficient time has elapsed the diamond will be severed.

The carbon particles or powder are mixed with suitable oil, as a vehicle, and filled into 85 a quill, from which the same is taken up by the edge of the rapidly-revolving cutting-disk.

The diamond-cross-cutting machine constructed as described and shown can be readily dismounted and the parts refitted or 90 repaired, and there is no delicate mechanism that is liable to reduce the efficiency of the machine, and the diamond may be severed thereby by attacking it from any point.

Having thus described my invention, what 95 I claim as new, and desire to secure by Letters Patent, is—

1. In a diamond-cross-cutting machine, the combination of a cutting-disk, means for operating the same, a suitably-supported guide-rail arranged transversely to the cutting-disk, a traverse-slide guided on said guide-rail, a feed-slide guided on the traverse-slide in a line transverse to the line of travel of the 100 traverse-slide, a clutch-holding device mounted on the feed-slide, a pulley at the inner end of the traverse-slide, a cord connected therewith and guided over said pulley, a weight suspended from said cord and movable with the traverse-slide, and means for connecting 105 said cord at different points in its length with said feed-slide, substantially as set forth.

2. In a diamond-cross-cutting machine, the combination of a cutting-disk, means for operating the same, a guide-rail supported transversely to the cutting-disk, a traverse-slide guided on said guide-rail and provided with a channel at its upper part, a feed-slide guided on the traverse-slide parallel with said channel, a clutch-holding device on the feed-slide, 110 a pulley at the inner end of the traverse-slide in line with said channel, a cord connected with the rear end of said feed-slide, in line with said channel, and passing through the latter and over said pulley, and a weight suspended from said cord and movable with said 115 traverse-slide, substantially as set forth.

In testimony that I claim the foregoing as my invention I have signed my name in presence of two subscribing witnesses.

GYULO ARMENY.
